DRY POWDERED SOAP COMPOSITION

Leonard H. Phillips, Somerville, Mass.

No Drawing. Application March 21, 1932,
Serial No. 600,362

3 Claims. (Cl. 87—5)

This invention relates to a dry soap composition adapted, when it is mixed with and certain of its ingredients are dissolved in a suitable quantity of water, to form a jelly-like semi-solid mixture or paste generally adapted for cleaning purposes and especially for use by mechanics, garage workers and the like.

The high water content of most hand soaps and pastes prevents profitable transportation thereof beyond a certain rather limited zone from its place of manufacture. The soap must also be contained in water tight metal cans, which increases its cost and weight and further restricts the profitable shipping distance. Hence the hand soap industry is a localized one.

It is an object of the present invention to provide a dry soap composition that contains all the ingredients necessary to make a hand soap or paste when a suitable quantity of water is added thereto, the composition being adapted to be sold in dry form in inexpensive paper or paper board cartons whereby manufacturing costs and transportation charges are minimized and the composition can be sold profitably at relatively great distances from its place of manufacture.

It is highly desirable that the soluble constituents of the soap composition shall be readily soluble in and rapidly assume a jelly form in cold water since hot water is not always available for use; and also that the insoluble constituents shall not agglomerate but shall remain dispersed throughout the mass. Such a composition constitutes a further object of the invention.

I have found that the addition of a certain amount of an alkali, as sodium or potassium hydroxide, for instance, renders the composition readily soluble in cold water, whereas the composition without the alkali would be but very slowly soluble in cold water. Hence a soap composition containing an alkali for rendering the composition readily soluble in cold water is a further object of the invention.

A further object is generally to improve soap compositions.

The soap composition embodying the present invention contains a suitable proportion of soap, preferably a white soap, in finely divided form as in granular, powder, or flake form. Any of the so-called soap powders now commercially available appear to be satisfactory although in my composition some are slightly more readily soluble in cold water than others, depending mainly upon the surface area of the particles. The composition also contains a suitable proportion of a finely divided inert material having abrasive

properties such as wood pulp fibres, sawdust and the like. I prefer sawdust, however, and particularly pine sawdust of finely divided form, the fineness being known to the trade as No. 3 sawdust. The sawdust does not dissolve with the soap when water is added to the present composition but, when treated in the manner presently to be described, remains dispersed throughout the jelly and acts as an abrasive in removing dirt that is loosened or softened by the soap. The mixture also contains a small percentage of an alkali and especially caustic soda in finely divided solid form. The caustic soda renders the soap rapidly soluble in cold water and other elements of the composition either soluble in or miscible with the water, as the case may be. The composition also contains a small proportion of finely divided rosin, a vegetable oil, as cotton seed or sassafras oil, or a mixture of vegetable oils, and a coloring matter preferably, although not necessarily, in powdered solid form. If not wanted, the coloring matter can be omitted. A composition having the following proportions of ingredients is satisfactory.

Sawdust	8	ounces	80
Soap	16	ounces	
Vegetable oil	1	ounce	
Caustic soda	2/5	ounce	
Rosin	1/2	ounce	
Coloring	q. s.		85

This amount when introduced into three quarts of water is sufficient to make approximately a gallon of soap paste.

In the process of making the dry composition the sawdust is tumbled or kept in agitation while the vegetable oil is sprayed onto the sawdust or is introduced therein in small quantities, the object being to deposit the oil on each particle of sawdust. The amount of oil is so small that the oiled sawdust is essentially dry and the sawdust particles do not adhere together. The tumbling operation may take about eight minutes depending upon the amount of sawdust that is treated with the oil. The specific time is not of importance except that it should be long enough to ensure a reasonably even distribution of the oil throughout the sawdust. The oiled sawdust is then tumbled with the balance of the elements of the composition, all of which are in powdered or finely divided form, the tumbling being continued for about fifteen minutes more or less, depending upon the amount of material in the batch, or until a reasonably uniform dispersion of the ingredients throughout the mass is ob-

tained. The composition can then be packaged in inexpensive paper or paste board cartons.

In using the composition it is intended that the contents of a carton shall be placed in a can or other receptacle with a specified amount of cold water, three quarts of the amount above given, and stirred until the dispersion of the composition throughout the mass of water is obtained. The soap and soluble components of the composition dissolve rapidly in cold water and in about fifteen minutes, forming a jel or paste that is ready for use.

The alkali contributes mainly to the rapid dissolving of the soap in cold water. If the alkali were not used it would take several days for the soap to dissolve in cold water, without agitation, and when a jel ultimately formed it would be found that a large amount of the water has separated out of the jel.

While caustic soda is herein employed as the alkali, caustic potash or sodium carbonate can be employed. In general any alkali is satisfactory although the amount of alkali that is used will depend upon the characteristics of the alkali.

More sodium carbonate will be required than caustic soda, for instance.

The vegetable oil and rosin is beneficial in several respects. Both more or less neutralize the caustic soda so that the action of the paste on the hands is not as harsh as it would be without these ingredients. The oil is rendered more miscible in the water by the alkali. The rosin is rendered more soluble by the alkali and any rosin that does not entirely dissolve in the paste is found to have a softening action upon paint and the like so that the cleaning action of the paste is enhanced. The manner in which the oil is applied to the sawdust prevents the sawdust from stratifying or collecting in one zone during the formation of the paste and maintains the sawdust dispersed uniformly throughout the water mixture at the time it begins to jel. Any vegetable oil appears to be satisfactory, but a mixture of equal parts of cotton seed and sassafras oil is preferred, the sassafras oil being desirable because of its odor.

Any coloring can be employed, the amount de-

pending upon the color desired. The coloring matter can be eliminated if not wanted.

If the coloring matter is in liquid form it can be introduced at the time of mixing the soap powder and oiled abrasive; and the amount of liquid is so small that it does not appreciably change the dryness of the mixture.

Instead of using a soap that contains but a relatively small amount of free alkali, a soap can be used that contains a large amount of alkali sufficient for the purpose above described.

I claim:

1. A soap composition in dry powder form adapted to form a homogeneous paste upon the addition of water, said composition containing a major proportion of powdered soap, sawdust in an amount sufficient to constitute an abrasive, sufficient vegetable oil to coat the sawdust particles to cause them to remain dispersed throughout the paste formed by the addition of water, an alkali such as caustic soda in an amount sufficient to render the oil water-miscible, and a neutralizing medium such as powdered rosin in an amount sufficient to neutralize the excess dissolved alkali in the paste.

2. A soap composition in dry powder form adapted to form a homogeneous paste upon the addition of water, said composition containing about two parts of powdered soap, about one part of sawdust, a vegetable oil in an amount sufficient to coat the particles of sawdust to cause them to remain dispersed throughout the paste formed by the addition of water, an alkali such as caustic soda in an amount sufficient to render the oil water-miscible, and a neutralizing medium such as powdered rosin in an amount sufficient to neutralize the excess dissolved alkali in the paste.

3. A soap composition in dry powder form adapted to form a homogeneous paste upon the addition of water, said composition containing the following materials in about the proportions stated: powdered soap 16 ounces, sawdust 8 ounces, vegetable oil 1 ounce, alkali as caustic soda $\frac{1}{2}$ ounce, and powdered rosin $\frac{1}{2}$ ounce.
